US00D827464S

(12) **United States Design Patent** (10) Patent No.: **US D827,464 S**
(45) Date of Patent: ** Sep. 4, 2018

(54) **AUTO DIAGNOSTIC SCANNER**

(71) Applicant: **AUTOPHIX TECH CO., LTD.**,
Shenzhen, Guangdong (CN)

(72) Inventors: **Jian Hao**, Guangdong (CN); **Qing Huang**, Guangdong (CN); **Yutao Zhao**, Guangdong (CN)

(73) Assignee: **AUTOPHIX TECH CO., LTD.**,
Shenzhen, Guangdong (CN)

(**) Term: **15 Years**

(21) Appl. No.: **29/601,654**

(22) Filed: **Apr. 25, 2017**

(30) **Foreign Application Priority Data**

Oct. 26, 2016 (CN) 2016 3 0525283
